US00D888661S

(12) **United States Design Patent** (10) **Patent No.:** **US D888,661 S**
(45) **Date of Patent:** **** Jun. 30, 2020**

(54) **CHARGER FOR MOBILE DEVICE**(71) Applicant: **SPIGEN KOREA CO., LTD.**, Seoul (KR)(72) Inventor: **Taesung Yoon**, Seoul (KR)(73) Assignee: **Spigen Korea CO., LTD.**, Seoul (KR)(***) Term: **15 Years**(21) Appl. No.: **29/699,479**(22) Filed: **Jul. 25, 2019****Related U.S. Application Data**

(63) Continuation of application No. 29/668,789, filed on Nov. 1, 2018, now Pat. No. Des. 856,926.

Primary Examiner — Rosemary K Tarcza(74) *Attorney, Agent, or Firm* — Heedong Chae; Lucem, PC(57) **CLAIM**

The ornamental design for a charger for mobile device, as shown and described.

DESCRIPTION

FIG. 1 is a front perspective view of the charger for mobile device showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines throughout the drawing figures depict portions of the charger for mobile device that form no part of the claimed design.

1 Claim, 8 Drawing Sheets(56)
